UNITED STATES PATENT OFFICE.

GEORGE M. HINKLEY, OF MILWAUKEE, WISCONSIN, ASSIGNOR OF ONE-HALF TO ALLIS-CHALMERS COMPANY, OF MILWAUKEE, WISCONSIN, A CORPORATION OF NEW JERSEY; ELIZABETH J. HINKLEY AND EDGAR L. WOOD, EXECUTORS OF SAID GEORGE M. HINKLEY, DECEASED.

EDGER.

No. 873,667.

Specification of Letters Patent.

Patented Dec. 10, 1907.

Application filed April 13, 1905. Serial No. 255,295,

To all whom it may concern:

Be it known that I, GEORGE M. HINKLEY, a citizen of the United States, residing at Milwaukee, in the county of Milwaukee and 5 State of Wisconsin, have invented certain new and useful Improvements in Edgers, of which the following is a specification.

The invention relates to edgers in which a plurality of saws are individually adjustable 10 along the saw arbor and a gang of saws is similarly but collectively so adjustable. Slides engage the saws or the gang collar and at their outer end divide into gabled branches extending in vertical parallel planes with 15 their lower ends engaging and sliding on horizontal parallel ways on the frame of the machine.

The accompanying drawing shows one form of the invention and in which,—

20 Figure 1 is an elevation, parts being broken away. Fig. 2 is a plan view of a slide with its two branches. Fig. 3 is a vertical sectional detail of one of the slide branches showing the gabled structure.

25 Fig. 4 is a broken vertical section of the edger on line 4, 5 in the direction of arrow 40, Fig. 1. Fig. 5 is a broken vertical section of the edger on line 4, 5 in the direction of arrow 50, Fig. 1.

30 In the machine shown, the edger frame consists of end supports 11, 12 connected by girders 13 at the front and back of the machine, the one at the back not being shown.

The saw arbor 14 is centrally longitudinally mounted in the edger and supported at 35 the ends of the edger in boxes 141 carried by arms 142 detachably fastened upon the end supports 11, 12. The saws 15 are mounted upon the arbor 14 so as to be individually, 40 longitudinally adjustable thereon by means of splines 16 and spline-ways 17. The gang of saws 18 is mounted on the arbor 14 in the same way but these saws are collectively adjustable, they being integrally mounted upon 45 a single collar 19.

The end support 11 is shaped (see Fig. 5) so that the saws 15, 18 may be put on or removed from the arbor 14 without interference therewith. It is only necessary in such 50 case to detach the arm 142 and box 141 from the end support 11.

Feed rolls 21 are provided and are operated from the saw arbor 14 by suitable connecting gearing 22, shown in part in Fig. 1.

Press rolls, not shown, are mounted above 55 the feed rolls 21. Guide rolls 23 are suitably provided at the ends of the machine.

Guides 30 for adjusting and spacing the saws longitudinally along the shaft consist of arms 31, each having at its outer end diverging branches 32, 33 extending in vertical planes, and a prop 34 extending downwardly from the arm 31 between the branches 32, 33. The guides 30 rest upon channel bar 35 bolted to the end supports 11, 12, and upon 60 an angle bar 36 bolted to the front girder 13 and formed on its upper surface with ways 42, 43 which are engaged by the suitably shaped feet of branches 32, 33 of the saw guides 30. The lower end of the saw guide 70 props 34 rest and during adjustment slide upon the upper surface of the bar 36 between the ways 42, 43.

The saw guides 30 have each at its inner end a pivoted arm 44 engaging the individual 75 saws at its free forked end, by means of pieces 45 of wood or other friction decreasing material. The arms 44 may be swung up on their pivots to allow removal of the saws.

The saw guide 30 for the gang of saws 18 80 has at its inner end, as shown in Fig. 5, an arm 441 pivoted to the arm 31 of the saw guide 30 in a similar manner to the arms 44 engaging the individually adjusted saws 15. The arm 441 is grooved on one side for the 85 reception and detachably bolting therein of a shank 442 integral with a collar 443 rotatably connected to the collar 19 upon which the gang of saws 18 is integrally mounted. The shank 442 extends within the periphery 90 of the saws. This rotatable connection is shown by means of an internally projecting ring 444 on the collar 443, fitting a corresponding groove 191 in the collar 19. Suitable oiling means 445 is provided in the collar 95 443.

When the gang of saws 18 is to be removed, the shank 442 is detached from the arm 441 which is then conveniently swung up out of the way. If the individual saws 15 are to be 100 removed, it is necessary to swing up arm 441 to clear the saws. After detaching the shank 442 from arm 441, the gang of saws 18 with the attached collar 443 can be slid off the arbor 14, the end supporting box 141 and 105 arm 142 having first been removed.

The saw guides 30 are longitudinally shiftable on the edger so as to adjust the saws to

positions ascertaining the distance between the saws and thus the required widths of lumber to be sawed. It becomes necessary to provide means for setting the guides to these adjusted positions. Such means as illustrated consist of the following parts. A channel bar 61 is supported longitudinally of the edger just above the saw guides 30 and is bolted to the frame at its ends. This channel bar 61 is placed at an angle of approximately 45 degrees measured in a transverse plane, its widest outer surface facing upwardly. Upon this surface is marked or attached a scale 62 and underneath and within the channel bar 61 is formed or attached a rack 63. Upon the outer end of each of the saw guides 30 and directly over the prop 34, is pivotally mounted in a transverse vertical plane, a holding lever 37. The outer end of the lever 37 is formed as a handle 38 and the inner end 39 curves upwardly under the channel bar 61 and is engageable with the rack 63. A coiled or other suitable spring 10 holds the lever 37 in engagement with the rack. Disengagement is effected by raising the handle 38.

The saws are manually shifted by raising handle 38 against the force of spring 10, thus disengaging the inner end 39 of lever 37 from the rack 63. While being thus held raised, the handle 38 serves as a means for longitudinally shifting the saw guides 30 together with the engaged saws 15 or gang saw collar 19 and saws 18 thereon. When the required position is reached, the handle 38 is allowed to be lowered by the spring 10 and the inner end 39 of the lever 37 engages with the rack 63, thus firmly holding the guides 30 and saws 18, 15 in the set position. Conveniently a pointer (not shown) is formed on the guide 30 adjacent the scale 62 to aid in adjusting for definite widths of lumber.

The branches 32, 33 are gabled, see Fig. 3, so as to shed sawdust and debris at the side of the ways 42, 43, Fig. 5 so that the similar branches are not prevented from coming close together in shifting the saws and guides.

Instead of the branches 32, 33 and the prop 34 of a guide 30, a single plane piece 50 may be substituted extending preferably vertically, but in any event, downwardly so as to shed debris. This plane piece would preferably take the form of a triangle with the edges of its base resting on the ways and its apex continued upwardly for attachment of the guide arm.

In accordance with the provisions of the patent statutes, I have described the principle of operation of my invention, together 60 with the apparatus which I now consider to represent the best embodiment thereof; but I desire it to be understood that the apparatus shown is merely illustrative and that the invention can be carried out by other means.

What I claim is,—

1. The combination in an edger of a saw arbor, a saw mounted loosely thereon for longitudinal movement with respect thereto, a guide engaged with said saw and extended horizontally therefrom, said guide being provided with two depending and downwardly diverging branches adapted to engage with a bar, said guide being further provided between said branches with a downwardly extended prop adapted to engage with said bar, and said bar. 65

2. The combination in an edger of a saw arbor, a plurality of saws loosely mounted thereon for longitudinal movement with respect thereto, a guide for each of said saws, 80 a bar, each of said guides being provided with a horizontally extended portion and two downwardly diverging branches adapted to engage with said bar, each of said guides being further provided with a downwardly extended prop also adapted to engage with said bar, corresponding downwardly extended branches of each of the guides being disposed in the same general plane longitudinally of the saw arbor, the structure of each 85 guide being the duplicate of the structure of each of the others, the diverging branches being adapted to nest when the guides are moved closely adjacent to each other. 90

3. In a gang-edger, the combination of a 95 saw-arbor, a plurality of saws longitudinally loosely mounted thereon, and guides for the saws having branches at the outer end of each guide, the guides nestable with their body portions side by side and their similar branches severally superposed. 100

4. In a gang-edger, the combination of a saw-arbor, a plurality of saws longitudinally loosely mounted thereon, equal and similar guides for the saws and gabled branches at 105 the outer end of each guide, the guide bodies nestable with their body portions side by side and the similar gabled branches superposed. 110

5. The combination in an edger of a saw arbor, a plurality of saws loosely mounted thereon for longitudinal movement thereof, a guide for each of the several saws, a bar disposed longitudinally of the saw arbor for supporting the guides, each of said guides being provided with a horizontally extended portion and with downwardly extended diverging branches, said guide being further provided with a downwardly extended prop at a point intermediate said branches, said prop being adapted to engage with said bar, the 115 upper surface of said branches being shaped to shed debris at the sides of said bar, and each of said branches being nestable with the corresponding adjacent branches of adjacent 120 guides. 125

6. In a gang-edger, the combination of a saw-arbor, a plurality of saws longitudinally loosely mounted thereon, similar guides for

the saws, ways for the guides, and branches at the outer end of each guide formed with an upper side for shedding debris at the side of the ways and nestable by superposing 5 similar branches.

7. In a gang edger, the combination of a saw arbor, a plurality of saws longitudinally loosely mounted thereon, and a plurality of adjacent guides of like form and dimensions 10 for the saws and having their outer ends extending downwardly and longitudinally of the saw arbor said outer ends having their entire extent confined to the space immediately adjacent to a vertical plane.
- 15 8. In a gang edger, the combination of a saw arbor, a plurality of saws longitudinally loosely mounted thereon, and a plurality of adjacent guides of like form and dimensions for the saws and having their outer ends extending downwardly and longitudinally of 20 the saw arbor said outer ends having their entire extent confined to the space between

two vertical planes spaced apart not more than half the length of the guide.

9. In a gang edger, the combination of a 25 saw arbor, a plurality of saws longitudinally loosely mounted thereon, and a plurality of adjacent guides of like form and dimensions for the saws having branches at the outer end of each of said guides extending in vertical 30 planes parallel to said saw arbor.

10. In an edger, the combination of a saw arbor, a saw longitudinally loosely mounted thereon, a guide for the saw having branches at its outer end extending in vertical planes 35 parallel to said saw arbor, and a prop for strengthening the guide.

In testimony whereof I affix my signature in presence of two witnesses.

GEORGE M. HINKLEY.
